F. MANKEY.

PANEL.

No. 17,140.

Patented Feb. 22, 1887

UNITED STATES PATENT OFFICE.

FREDERICK MANKEY, OF WILLIAMSPORT, PENNSYLVANIA.

DESIGN FOR A PANEL.

SPECIFICATION forming part of **Design No. 17,140, dated February 22, 1887.**

Application filed December 30, 1886. Serial No. 233,048. Term of patent 7 years.

To all whom it may concern:

Be it known that I, FREDERICK MANKEY, of Williamsport, Lycoming county, Pennsylvania, have invented and produced a new and original Design for Panels, of which the following is a specification.

Figure 1 represents my new design, and Figs. 2 and 3 modifications therof.

Similar letters of reference indicate like parts.

My design consists in the six quadrangular elevations A A', with rounded edges. Parallel to the sides of said elevations are beads B, said beads having upper rounded surfaces. Between the elevations and the beads are channels C. Between the extremities of the beads are rounded elevations D. Between the rounded elevations D and the ends of the beads are narrower channels E. The general

effect is of a multiplicity of quadrangular elevations and beads covering the area of the panel. This effect I may modify, as in Figs. 2 and 3. In lieu of certain of the rectangular elevations appearing as of parallelograms, as at A, Fig. 1, all may appear squares, as in Figs. 2 and 3 at A'.

I claim—

The design for a panel, substantially as herein shown and described, consisting in the six quadrangular elevations A A', having upper flat surfaces and rounded edges, the rounded beads B, having upper rounded surfaces, the rounded elevations D, and channels E C.

FREDERICK MANKEY.

Witnesses:

C. F. MANKEY,
LEONHARD KNAUSS.
